UNITED STATES PATENT OFFICE

GUSTAV EGLOFF AND HARRY P. BENNER, OF CHICAGO, ILLINOIS, ASSIGNEES TO UNIVERSAL OIL PRODUCTS COMPANY, OF CHICAGO, ILLINOIS, A CORPORATION OF SOUTH DAKOTA

PROCESS OF CRACKING ROSIN

Application filed December 20, 1920, Serial No. 432,070. Renewed March 15, 1928.

Among the salient objects of our invention are to provide a process of converting resinous material such as rosin from the destructive distillation of wood in the presence of water or steam to produce light oils therefrom, as conversion products resulting from heat and pressure; to provide a cracking process for treating resinous material and water to produce light oils therefrom; to provide a cracking process of converting resinous material into light oils under heat and an increment rise in pressure per minute of processing of 200 pounds to the square inch and upwards; to provide a cracking process of converting resinous material and water to produce light oils therefrom, exerting a vapor pressure on the system in excess of 5000 pounds to the square inch; to provide a cracking process to produce an oily material lighter than 15 degrees Baumé and containing an unsaturated hydrocarbon content of 10% or more; and in general to provide improved products and process of making same.

An apparatus suitable for carrying out the invention is disclosed in the drawing, in which the single figure is a side elevation of the apparatus with parts shown in section.

The apparatus comprises a shell still 1 constructed to withstand high pressures, which still is mounted above the heating chamber 2 of a suitable furnace. The furnace is provided with a combustion chamber 3, in which are positioned a plurality of baffles 4. The furnace is heated through the medium of the burners 5, which discharge into the combustion chamber 3. A flue 6 leads the products of combustion from the heating chamber 2.

The still 1 is provided with a vapor outlet 7, controlled by a suitably constructed valve 8. If desired, the still may be provided with a pressure gage 9, as well as with a pyrometer 10. The still is preferably provided with a removable manhole cover 11, as well as with a draw-off line 12 controlled by a suitable valve 13.

A typical run of this process is as follows: The high pressure still 1 is charged with resinous material such as rosin 90% by weight, and 10% by weight of water and said high pressure still is heated until a maximum pressure of 5600 pounds was obtained and a temperature of 910 degrees F. in the liquid.

The following table discloses the operating

conditions under which the process is carried out:

Fired 2:40 p. m.

Time	Liquid temperature degrees F.	Pressure pounds per square inch	Time	Liquid temperature degrees F.	Pressure pounds per square inch	60
2:45			:50	611	900	
3:15	105		:55	626	1,050	
:15	170		5:	654	1,300	
:30	280		:05	685	1,650	
:45	360		:10	721	2,000	
4:15	410		:15	752	2,250	
:15	476		:20	783	2,600	
:17	487		:25	802	2,950	
:20	498	150	:30	815	3,200	
:25	516	300	:35	835	3,700	
:30	535	400	:40	870	4,350	
:35	551	500	:43	892	5,000	
:40	575	625	:45	905	5,400	
:45	595	775	:47	910	5,600	

It is to be noted that the maximum liquid temperature was 910° F. and that at this temperature the pressure was 5600 pounds. No substantial decomposition occurred before the temperature reached 650° F. and the pressure reached substantially 1200 pounds per square inch.

The following table illustrates the characteristics of the oil recovered from the heat and pressure treatment of rosin and water under our process found upon analysis of this oil:

Bé. Gr. 15.7. Fired 8:50 a. m. over 8:58 a. m. Init. B. P. 118° F. 90% @ 716° F. Charge 500 cc.	Unsaturates 14%. Time to distil 1 hr. 57 mins. Range 598° F. Color before distillation greenish black.	85

Per cent over	Temperature °F.	Baumé gravity	Unsaturates per cent	90
5	210	62.8	27	
10	330	44.4	28	
15	386	35.6	23	
20	446	29.1	18	
25	510	25.5	15	
30	566	18.5	15	
35	590	13.7	13	
40	610	11.2	13	
45	618	11.1	9	
50	626	9.9	13	
		Spec. gr.		90
55	634	1.005	11	
60	642	1.008	11	
65	650	1.013	11	
70	656	1.015	8	
75	662	1.016	9	
80	680	1.016	11	
85	695	1.014	12	
90	716	1.025	11	

2% drips end of run. 8% tar bottoms and losses.	Separated 75 cc. of free water from charge of rosin and water.	100

It is to be noted that the oil recovered from the rosin and water when treated under our process had a gravity of 15.7° Baumé, an initial boiling point of 118° F., and that 90% of the oil boiled below 716° F. There was only 8% loss from tar bottoms.

The product recovered possesses drying characteristics of the character of turpentine. It constitutes a light oil and is suitable for use as a drying agent in paints and various compositions where a drying oil is required.

We claim as our invention:

1. A process of cracking rosin in the presence of water, which consists in introducing said mixture to a still, in subjecting the mixture to heat and pressure sufficient to raise its temperature above 900° F. and to generate a vapor pressure exceeding 5000 pounds per square inch to convert a substantial portion of the mixture into a light oily product.

2. A process of cracking rosin in the presence of water, which comprises introducing the mixture into a still, in raising the temperature thereof in excess of 700° F. and in generating a vapor pressure on the mixture in excess of 1000 pounds per square inch to convert a substantial portion of the solid constituents of the mixture into a light oily product.

3. A process of cracking rosin in the presence of water, which consists in introducing the rosin and water into a still and heating the same to a temperature in excess of 700° F. and under a vapor pressure in excess of 1000 pounds per square inch to convert more than 20% of the solid material into oily constituents lighter than 30 degrees Baumé.

GUSTAV EGLOFF.
HARRY P. BENNER.
